UNITED STATES PATENT OFFICE.

WILLIAM G. IMLACH, OF BERWYN, ILLINOIS.

METHOD OF MAKING RAILS FOR PRINTING-PLATES.

1,392,502.

Specification of Letters Patent.

Patented Oct. 4, 1921.

Application filed October 25, 1920. Serial No. 419,297.

To all whom it may concern:

Be it known that I, WILLIAM G. IMLACH, a citizen of the United States, and resident of Berwyn, in the county of Cook and State of Illinois, have invented certain new and useful Improvements in a Method of Making Rails for Printing-Plates, of which the following is a specification.

My invention relates to devices for use 10 in connection with printing plates and particularly to a method of producing the T-shaped rails which are attached to the backs of curved multigraph plates.

It is customary in the production of plates 15 of the character just described to provide undercut ribs which are secured to the backs of mimeograph plates in order to adapt the plates for ready attachment to the cylinders employed in such devices. It has been the 20 practice heretofore to form such ribs or rails of electrotype or similar soft metal such as is employed for backing the printing plates. It has been found in practice, however, that such rails are fragile and 25 readily become bent and broken. An object of the invention here disclosed is to provide rails of this character having a suitable reinforcement by means of which the rails are strengthened and will resist the 30 wear and strains incident to service.

In accordance with the invention here disclosed I construct these rails by first providing a suitably shaped mold and then electrolytically deposit a thin layer of copper 35 therein. The thus-formed shell is then filled with soft metal to the proper thickness thus providing a rail having the characteristics described. Preferably the copper shell is formed with a relatively large number 40 of adjacent grooves—or in effect rail webs—and after the soft metal is cast therein the shell is sawed along lines parallel to the rails, thus forming a plurality of T-rails.

The invention will be more readily understood 45 by reference to the accompanying drawing, wherein,

Figure 1 is a cross sectional view through a form of a mold;

Fig. 2 shows the same mold after a cop- 50 per deposit has been made therein;

Fig. 3 shows the copper shell after the soft metal has been poured therein;

Fig. 4 is a perspective view, somewhat 55 enlarged, of the bottom of the casting before the rails have been sawed up;

Fig. 5 is a perspective view of one of the completed rails, and

Fig. 6 is a perspective view of the printing plate to which the rails have been applied.

According to the method here disclosed I 60 prefer to first form a mold 10 of wax or similar material, this mold having a plurality of rectangular grooves 11 therein. In a well known manner the mold is then electrolytically lined with copper, indicated at 65 12 in Fig. 2. The thickness of the copper shell thus formed will be determined according to the desired extent of reinforcement. Thereafter the shell 12 is removed from the mold and is filled with soft metal, indicated at 70 13 in Fig. 3, the thickness of which will determine the height of the rail to be produced. As shown in Fig. 4, there is formed a plate having a flat surface on one side and on the other side a copper surface 75 consisting of alternate grooves 14 and ribs 15.

Thereafter the plate is sawed along the lines 16, of Fig. 3, thus producing a plurality of the rails 17, shown in Fig. 5. 80 These rails are thereafter cut to proper length and soldered or otherwise secured to a plate 18, as shown in Fig. 6. The wearing surface of the rails; that is, the web and the underside of the head, is copper covered 85 the harder metal taking the wear and suitably reinforcing the otherwise fragile rail.

Obviously the shell of copper may be formed in a manner other than that disclosed herein and similar results secured. I 90 do not therefore wish to be limited except as indicated in the appended claims.

I claim:

1. The method of making rails for plates which consists in providing a relatively hard 95 metal shell having a groove therein, then casting soft metal in said shell and filling the groove, then cutting the reinforced casting to provide a T rail.

2. The method of making T rails for 100 plates consisting in providing a thin, hard metal shell having a plurality of parallel grooves therein, then casting metal in said shell, then cutting the casting and shell along lines parallel with the grooves to form 105 T rails.

3. The method of making T rails for plates consisting in providing a thin, hard metal plate having a plurality of laterally offset portions forming parallel grooves 110

then casting soft metal on said plate and filling said grooves, then cutting the plate and the adhering soft metal along lines parallel to said grooves and at a point spaced 5 away from the grooves thereby forming **T** shaped sections having copper reinforcement on one side.

4. The method of making rails for printing plates which consists in providing a 10 mold having grooves therein, then electrolytically depositing a relatively hard metal in said mold and on the walls of said grooves, then casting a soft metal on the hard metal shell and then cutting the casting and shell alongside of the ribs formed 15 by the metal deposited in said groove, thereby providing a reinforced **T** rail.

5. The method of making rails for printing plates which consists in providing a 20 mold having grooves therein, then elec-

trolytically depositing copper in the mold thereby forming a copper shell having alternate ribs and grooves, then casting electro-type metal on one side of the plate thereby filling the grooves, then cutting the thus-formed plate along lines parallel to but removed from the filled grooves thereby forming reinforced **T**-rails.

25

6. A rail for use on printing plates consisting of a body of soft metal of **T**-shape 30 having a covering of harder metal at the points of operative engagement with a co-operating part.

7. A rail of **T**-shape covered with copper on its web and the underside of its head, 35 the body of the rail being composed of softer metal.

Signed at Chicago, Illinois, this 22nd day of October, 1920.

WILLIAM G. IMLACH.
